J. P. YOUTZ

PROJECTION LANTERN

Filed April 30, 1924

Inventor:
Jesse P. Youtz,

by *Alexander S. Lane*

His Attorney

UNITED STATES PATENT OFFICE.

JESSE PAUL YOUTZ, OF RIO DE JANEIRO, BRAZIL, ASSIGNOR TO GENERAL ELECTRIC COMPANY, A CORPORATION OF NEW YORK.

PROJECTION LANTERN.

Application filed April 30, 1924. Serial No. 710,149.

My invention relates to projection lanterns of a type which is especially adapted for use for motion pictures.

In motion picture machines heretofore the lamp housing has been adjusted with respect to the supporting or guide plate or with respect to the optical axis of the objective lens by the operation of thumb bolts that serve to secure the lamp housing to the guide plate. Such an arrangement has been found to be awkward and slow. My invention contemplates the use of a construction by means of which such adjustments may be rapidly and conveniently made.

The means for accomplishing the foregoing are hereinafter more fully set forth and claimed, reference being had to the accompanying drawing.

Referring to the drawing it will be seen that Fig. 1 is a view in perspective. This view shows the adjusting mechanism in its relation to the guide or supporting plate and housing. A section of the guide plate is broken away to more clearly illustrate the details.

Fig. 2 is a view in elevation taken partly in section.

Referring more in detail to the drawing, in Fig. 1 the housing 2 is shown at the right of the supporting plate, which latter is adapted to be secured to the frame of the projector. The holes 4 are provided for this purpose. The plate is also provided with four guide slots 5. A set of bolts 6 are also provided which are secured to the back part of the housing and which project through the slots 5 in the guide plate. These bolts are threaded and have winged nuts 7 between which and the housing the back of the plate 3 is located. Between the upper nuts 7 and the plate, I provide an angle beam 8 serving as a cross-bar between the two upper bolts 6. This beam is in threaded engagement with a thumb bolt 10 which serves as a drag screw. This screw passes through the supporting angle plate 11. The two sides of this plate extend at right angles to each other. One of the sides is horizontally disposed and is provided with a groove 12 near the forward edge thereof which receives the upper edge 13 of the guide plate 3. The

other side 14 of the plate which extends at right angles to the horizontal side rests in engagement with the outer edge 15 of the beam 8. With this construction, the housing 2 may be raised or lowered by turning the drift screw 10. For example, by turning the screw clockwise, as viewed from above, the beam 8 may be raised and therefore the housing 2 also raised. During this operation the beam 8 slides against the guide plate 3 and also against the inner surface of the side 14 of the plate 11. By reversing the direction of rotation of the screw 10 the housing may be lowered.

Assuming that the optical axis of the housing is too high or too low with respect to the optical axis of the aperture and the object lens, the housing may be adjusted to bring the two optical axes into alinement by means of the drift screw 10. After the proper alinement is obtained the housing may then be locked in its adjusted position by tightening all of the nuts, thus clamping the housing against the guide plate and at the same time locking the beam against further movement.

I have not actually shown the reflector, light source, condensing lens, aperture, or objective lens because these elements are well known and their relation perfectly understood.

While I have shown my invention in the form of a specific embodiment to comply with the requirements of the statutes, I wish it understood that I do not intend to be limited to the specific construction shown inasmuch as, in view of the disclosure, obvious modifications will readily suggest themselves to those familiar with this art without departing from the spirit of my invention or the scope of the claim herein.

What I claim as new and desire to secure by Letters Patent of the United States, is:—

In a projector, a frame, a housing, an upright plate adapted to be screwed to the frame of the projector, guide openings in the plate, a pair of bolts projecting through said guides, a cross beam suspended between said bolts behind the plate whereby the housing may be raised and lowered by raising and lowering said beam, and sliding said bolts in said guides, a support for said beam

in the form of an angle piece with one leg of the piece supported by the plate and the other leg of the piece resting against said beam and in sliding engagement therewith, and a threaded element between the piece and the beam for raising and lowering the beam and thereby operating the housing, said

threaded element being supported by the angle piece and in threaded engagement with said beam.

In witness whereof, I have hereunto set my hand this 15th day of April 1924.

JESSE PAUL YOUTZ.
